[57] CLAIM

The ornamental design for a wiper blade assembly clip, as shown and described.

DESCRIPTION

FIG. 1 is a perspective view of a wiper blade assembly clip showing our new design;

FIG. 2 is a perspective view of the wiper blade assembly clip of FIG. 1, viewed from the underside of the wiper blade assembly clip;

FIG. 3 is a top view of the wiper blade assembly clip shown in FIG. 1;

FIG. 4 is a side view of the wiper blade assembly clip shown in FIG. 1, the opposite side view being a mirror image;

FIG. 5 is a bottom view of the wiper blade assembly clip shown in FIG. 1;

FIG. 6 is a front view of the wiper blade assembly clip shown in FIG. 1; and,

FIG. 7 is a rear view of the wiper blade assembly clip shown in FIG. 1.

UNITED STATES PATENT AND TRADEMARK OFFICE
CERTIFICATE OF CORRECTION

PATENT NO. : Des. 372,217
DATED : July 30, 1996
INVENTOR(S) : Barry J. Abott, et al

Page 1 of 4

It is certified that error appears in the above-identified patent and that said Letters Patent is hereby corrected as shown below:

The title page, showing an illustrative figure, should be deleted and substitute therefor the attached title page.

Delete Drawing Figures 1-6, and substitute therefor the Drawing sheets, consisting of Fig.1-6, as shown on the attached pages.

Signed and Sealed this
Fifteenth Day of July, 1997
